CLAIM

The ornamental design for a wrist band monitor as shown and described.

DESCRIPTION

FIG. 1 is a front view of a wrist band monitor showing my new design;

FIG. 2 is a rear view of the wrist band monitor;

FIG. 3 is a left side view of the wrist band monitor;

FIG. 4 is a right side view of the wrist band monitor;

FIG. 5 is a top view of the wrist band monitor;

FIG. 6 is a bottom view of the wrist band monitor; and,

FIG. 7 is a top front side perspective view of the wrist band monitor.

The broken lines in the drawings show portions of the wrist band monitor that form no part of the claimed design.

1 Claim, 4 Drawing Sheets(56)
